(57) **CLAIM**

The ornamental design for a railing bracket as shown and described.

DESCRIPTION

FIG. 1 is a front perspective view of a railing bracket showing the new design;

FIG. 2 is a top view thereof;

FIG. 3 is a bottom view;

FIG. 4 is a left side view;

FIG. 5 is a right side view;

FIG. 6 is a front view; and,

FIG. 7 is a rear view.

The surface shading is intended to depict surface contour and forms no part of the claimed design.
